UNITED STATES PATENT OFFICE.

JOHN H. VAN SICKELS, OF MONTREAL, QUEBEC, CANADA, ASSIGNOR TO GENERAL CIGAR COMPANY LIMITED, OF MONTREAL, CANADA.

DISPLAY CASE.

Application filed April 14, 1925. Serial No. 23,101.

This invention relates to new and useful improvements in display cases and, particularly to cases having a plurality of independently hinged covers, and the object of 5 the invention is to provide a case of the class stated having means which will prevent unauthorized unlocking of any or all of the covers.

Another object is to provide a case of the 10 class stated which will have means for automatically locking any one, or all of the covers on the closing of same.

A further object is to provide a display case which will be simple in construction, attractive, and neat in appearance, and efficient as regards preservation of the goods contained therein, and the manner of displaying same.

In my invention I provide a display case 20 having a plurality of independently hinged covers formed in such a manner that goods placed within the case will be displayed through transparent material forming the central portion of the covers.

25 Spring controlled locking levers form locking means for the covers, the unlocking of which, is controlled by a cam shaped lever positioned at the back of the case, and connected to the locking levers in such a manner 30 that all of the covers may be unlocked in unison. The case is provided with supports and positioning means for the goods, and means are provided within the case to preserve such articles as cigars, cigarettes or 35 the like which require a moistened atmosphere to assist them in retaining their quality and market value.

In the drawings—

40 Figure 1, is a perspective view of my improved display case with parts shown in section.

Figure 2, is a longitudinal sectional view of the case taken on the line 2—2 Figure 1.

45 Figure 3, is a sectional end view taken on the line 3—3, Figure 2.

Figure 4, is a perspective view of one of the covers.

Figure 5, is a perspective view of one of the locking levers.

50 Figure 6, is a perspective view of the cam lever controlling the locking levers.

Referring more particularly to the drawings which illustrate one form of my invention, namely, a display case suitable for 55 counter use, 11 designates the bottom of the

case, 12 the sides, 13 and 14 the back and front respectively. It will be noticed that the back of the case is made higher than the front, and that the upper edges 15 of the sides slope downwardly towards the front of the case. Extending from side to side of the case, and attached in any suitable manner to the upper edge 15 of said sides are the 60 cover supports 16, which are shown in section, and are of channel formation in Figures 1 and 2, but this is for illustrative purposes only, and these supports may be made of any suitable cross section, which will be strong enough to support the covers. Attached to the cover supports by means of the 65 hinges 17, are the cover frames 18 which are provided with transparent centre portions 19, through which, the goods placed within the case may be displayed.

The cover frames are of rectangular formation, with grooves 20 formed in their inner faces 21, and the sheets of glass or other transparent material forming the centre portions are held within the grooves by means of the cushioning members 22, which 70 may be made of rubber tubing or like resilient material. A slot 23 is cut or formed in the lower face, and in one side 24 of each of the frames, so that the hooked ends 25 of the locking levers 26 will pass through 75 said slots, and engage with the edges 27 of the slots to lock the covers. The levers 26 are pivotally mounted on brackets secured to one side of the casing, and the hooked ends pass through slots in the upper edge 15 80 of the casing, said upper edges being strengthened by being turned first inwardly, and then downwardly, as shown in detail in 85 Figure 3.

The lower ends 28 of the levers extend beyond the brackets, and are coupled together by means of the link 29 pivotally attached to the levers by means of the pins 30, so that on movement of said link all the locking levers 90 will move in unison.

Pivotally attached to, and in close proximity to one end of the link is the connecting rod 31, one end of which is adapted to pass through an aperture 32 formed or cut in the back of the casing. An operating 105 handle 33 is pivotally attached to the end of the connecting rod by means of the pin 34. The handle is so formed that the distance between the centre of the pin 34, and the surface 24 is less than the distance be- 110

tween said centre, and the surface 36, so that the handle when turned, or rotated on the pin 34 will pull the connecting rod towards the back of the box, thereby operating the locking levers through the attached link.

A collar 37 may be secured to the connecting rod, and a spring 38 surrounding said rod may be placed between the collar and the inner surface of the back of the case.

A plurality of spaced supports 39 may be secured to the inner surface of the bottom of the box, and may be made in such a manner that the upper surfaces 40 of said supports lie parallel with the upper edges of the sides of the casing, so that boxes of cigars, cigarettes or the like will be held in such a manner that their contents will be displayed to the best advantage through the covers. Pockets 41, secured to the inner surfaces of the sides of the casing and at one end thereof, by means of the brackets 42, are provided as holders for the humidors 43, which consist of open ended frames 44 of rectangular formation between the sides of which an absorbent material 45 may be placed. Slots 46 may be formed in the frames to assist in distributing the moisture held by the absorbent material. The frames 44 may be made of thin flexible material, so that the upper edge 47 may be bent to open the frame to facilitate refilling of same when required. Distance pieces 48 may be attached to the sides of the casing to form a positioning means for boxes of less area than that bounded by the cover supports, the hinge supporting members, and the back or front of the casing. Modifications may be made without departing from the spirit of the invention.

In operation, boxes of cigars or cigarettes or the like are placed on the upper edges of the supports, and the sides of the boxes are held in position by the coming in contact with the vertically disposed portions of the upper edges of the case, or cover supports. The covers are then closed by dropping them. In dropping, the edges of the slots contact with the curved ends of the locking levers, and cause same to move against the spring on the connecting rod until they spring into the locking position. The case covers can only be unlocked by operating the cam lever.

It will be seen that a case, constructed in the manner disclosed cannot be opened except by an authorized person, as the lever is

placed in such a position that it can only be operated from the back of the counter upon which the case is placed. It will also be seen that one or all of the case covers can be unlocked if desired. The case is so constructed that the goods may be displayed to the best advantage, and by providing humidors within the casing the cigarettes, cigars or the like will be kept in good condition.

Having thus described my invention, what I claim is:

1. A merchandise display case equipped with a plurality of doors extending transversely across the top of the case and independently hinged thereto so as to be capable of individual movement to and from closed position, a plurality of latches pivoted to one side of the case and having the upper terminals thereof hooked to automatically engage over portions of the doors when the latter are moved to closed position, a link interconnecting said latches and pivoted thereto, a connecting rod pivoted at one end to the link and having the other end protruding outwardly through an opening formed in the rear of the case, handle means carried by the outer end of said connecting rod and operable to impart reciprocal movement to the rod and a spring encircling the rod between an abutment thereon and the rear wall of the case and serving to normally maintain the latches in a door-engaging position.

2. A merchandise display case provided at the top with spaced transversely extending door supports, doors hinged to said supports adapted, in closed position, to bridge the spaces between the supports and to form a closed top for the case, said doors being capable of independent movement to and from closed position, latch members intermediately pivoted to one side of the case and having their upper terminals hooked and co-acting with openings formed in the doors to lock said doors upon movement thereof to closed position, a link pivoted to said latches, spring means for yieldably maintaining said latches in door securing position and handle means connected to said link and operable to simultaneously move all of the latches to door releasing position against the resistance of said spring means.

In witness whereof, I have hereunto set my hand.

JOHN H. VAN SICKELS.
